(57) **CLAIM**

The ornamental design for pet glasses as shown and described.

DESCRIPTION

FIG. 1 is a front, right side, top perspective view of the pet glasses showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the pet glasses that form no part of the claimed design. The oblique lines shading shown in the drawings indicates a transparent or translucent surface.

1 Claim, 8 Drawing Sheets
